UNITED STATES PATENT OFFICE.

JOHN HENRY KENDLE, OF BOGNOR, ENGLAND.

LIGHTING DEVICE.

SPECIFICATION forming part of Letters Patent No. 634,004, dated October 3, 1899.

Application filed May 10, 1899. Serial No. 716,218. (No model.)

To all whom it may concern:

Be it known that I, JOHN HENRY KENDLE, a subject of the Queen of Great Britain, residing at Bognor, in the county of Sussex, England, have invented certain new and useful Improvements in Lighting Devices, of which the following is a full and complete specification, such as will enable those skilled in the art to which it appertains to make and use the same.

This invention relates to lighting devices, and particularly to that class of such devices employing a fuse and designed to hold matches; and the object thereof is to provide an improved device of this class which may be conveniently carried in the pocket and used for lighting a cigarette, pipe, or cigar, and for other and similar purposes whenever desired.

The invention is fully disclosed in the following specification, of which the accompanying drawings form a part, in which—

Figure 1 is a plan view of my improved lighting device; Fig. 2, an end view thereof; Fig. 3, a section on the line 3 3 of Fig. 1; and Fig. 4, a view similar to Fig. 2, showing a modified form of construction.

In the drawings forming part of this specification the separate parts of my improvement are designated by the same letters of reference in each of the views, and in the practice of my invention I provide a box or casing A, which is preferably oblong in form and provided with a hinged cover B, and said box or casing is also provided with a transverse partition C, whereby two separate compartments D and E are formed.

The compartment E is designed to serve as a receptacle for matches, and mounted in the compartment D is a shaft F, which is provided with a handle G, which projects from the side of the box or casing and by which the shaft may be turned, and wound on said shaft, within the compartment D, is a fuse H, which is preferably chemically prepared and adapted to be easily ignited and to burn in a strong wind or wherever and whenever desired, and one end of the box or casing A is provided with two circular openings K and L, through one of which the end of the fuse H is passed, as shown in Figs. 1, 2, and 3, and

in practice a match is taken from the compartment E and ignited, and the fuse H is lighted, and after it has been used for the desired purpose the flame is extinguished by folding said end of the fuse up over the top of the box or casing and placing it beneath a flexible extinguisher M, which is secured to the top of the box or casing at N.

In order to extinguish the lighted fuse, the flexible extinguisher M is passed downwardly thereon, and after the said fuse is extinguished the end thereof is passed backwardly into the box or casing through the opening L, as shown in dotted lines in Fig. 1, the object of this operation being to prevent soiling the pocket or other articles by the extinguished end of the fuse.

In Fig. 4 I have shown a modification in which I substitute for the circular opening L a notch or recess O, which opens upwardly when the hinged lid or cover B is raised, and with this form of construction the end of the fuse may be placed in said notch or recess and the lid closed thereover. This form of construction is more convenient than that shown in Fig. 2; but either form may be employed, as desired. The fuse H is easy to ignite, and when once ignited will burn in a strong wind, and in practice I also form on some part of the device a serrated surface, on which a match may be ignited, and this serrated surface in the construction herein described is shown at P on the cover B.

Having fully described my invention, I claim as new and desire to secure by Letters Patent—

1. A lighting device, comprising a box or casing having a transverse partition, and a hinged cover, a shaft which is mounted in one of the compartments formed by said partition, and a fuse which is wound thereon, said box or casing being also provided at the end adjacent to said shaft with an opening through which the fuse is passed, and another opening adjacent thereto, substantially as shown and described.

2. A device of the class described, comprising a box or casing having a transverse partition forming two compartments, a shaft mounted in one of said compartments, a fuse wound thereon, said box or casing being also

provided with a hinged cover, and with an extinguisher secured thereto, substantially as shown and described.

3. A device of the class described, comprising a box or casing having a transverse partition forming two compartments, and having a hinged cover, a flexible extinguisher secured to said cover, a shaft mounted in one of said compartments, a fuse wound thereon, and means whereby the end of the fuse may

be passed through the end of the box or casing, substantially as shown and described.

In testimony that I claim the foregoing as my invention I have signed my name, in presence of the subscribing witnesses, this 20th ¹⁵ day of April, 1899.

JOHN HENRY KENDLE.
